SHIPMENT BLOCKING MEANS

Lancelot E. Wenhana, Pittsfield, Mass., assignor
to General Electric Company, a corporation of
New York

Application April 10, 1934, Serial No. 719,902

4 Claims. (Cl. 175—336)

My invention relates to shipment blocking means and more particularly to a novel construction for preventing motion of the normally movable elements of a contact making voltmeter during shipment of the meter.

Contact making voltmeters and other similar devices having relatively delicate movable parts are likely to have these parts injured and the calibration of the meter disturbed due to vibration and rough handling of the meter during its shipment from the manufacturer to the purchaser.

In accordance with my invention, I provide a novel and extremely simple shipment blocking arrangement for preventing injury of the meter parts during its shipment. This arrangement consists essentially of a shipment blocking screw which is threaded into the core of the operating solenoid of the meter and into a stationary element associated with the meter, thereby effectively blocking motion of the core in any direction.

An object of my invention is to provide a novel shipment blocking arrangement.

A further object of my invention is to provide a novel and simple means for preventing movement of the normally movable elements of a contact making voltmeter during its shipment.

My invention will be better understood from the following description taken in connection with the accompanying drawing and its scope will be pointed out in the appended claims.

In the drawing, Fig. 1 is a perspective view of the upper portion of a contact making voltmeter to which my invention is applied, and Fig. 2 is a part longitudinal sectional view along the blocking screw and showing the details of construction of my invention.

Referring now to Fig. 1, there is shown a contact making voltmeter comprising a base member, or plate, 1, to which is fastened in any suitable manner an enclosed operating solenoid magnet 2. The solenoid magnet is provided with a core member 3 which is attached in any suitable manner to a pivotally mounted contact beam 4 which is mounted in delicate bearings and which carries movable contacts 5 for cooperation with stationary contacts 6. My invention is not concerned with the various structural details of the contact beam mounting, or the stationary contact mounting, of the meter shown in Fig. 1, and these details are shown in more detail and are claimed, respectively, in application Serial No. 719,901, filed April 10, 1934, in the name of G. H. Fagley, and application Serial No. 719,898, filed

April 10, 1934, in the name of F. J. Champlin, both of said applications being assigned to the assignee of the present application.

The contact beam 4 is also provided with an armature member 7 which is adapted in operation to be attracted by enclosed holding magnets 8 in a well known manner.

Supporting means 2 for the solenoid is provided with brackets or lugs 9 and 10 having holes therein, and a hole is provided in the core member 3, these holes all being so placed that when the core member 3 is in a position in which no undue strain is placed on the movable elements associated with the contact beam 4, all three of these holes will be in alignment. The hole in the core 3 is 15 threaded and one or both of the other holes is threaded. As shown, the hole in the back bracket 10 is threaded, but if desired, the hole in bracket 9 may also be threaded, or the hole in member 9 may be threaded and the hole in member 10 20 may not be threaded.

Adapted to be passed through the holes when they are in alignment is a shipment blocking screw 11.

When it is desired to ship the meter, the screw 11 is passed through all three holes and due to the fact that it is in threaded engagement with the hole in core 3 and also is threaded to one of the fixed members attached to the enclosing means for the solenoid, the core 3 is effectively 30 blocked from motion in any direction. Thus, the threads prevent it from moving axially along the screw, while the screw prevents vertical motion of the core or motion in any radial direction. Consequently, the parts are prevented from damaging themselves during shipment and the meter 35 may be accurately adjusted at the factory so that when it is ready to be installed all that is necessary is that the screw 11 be removed, and the meter will be ready to go into service. During 40 normal operation of the meter, of course, the screw 11 is removed.

While I have shown and described a particular embodiment of my invention, it will be obvious to those skilled in the art that changes and 45 modifications may be made without departing from my invention, and I, therefore, aim in the appended claims to cover all such changes and modifications as fall within the true spirit and scope of my invention.

What I claim as new and desire to secure by Letters Patent of the United States is:

1. In a contact making voltmeter, in combination, an operating solenoid magnet, supporting means therefor, a core therein, and means for 55

- blocking said core against movement relative to and stationary means having aligned holes on opposite sides of the hole in said core, one of the holes in said means also being threaded whereby if a shipment blocking screw is passed through all of said holes so as to have its threads engage the threads of said holes said core will be blocked from motion in any direction. 5
5. 2. In a contact making voltmeter, in combination, an operating solenoid magnet, a relatively movable core therein, means which is relatively immovable with respect to said magnet having a threaded hole therein whose axis passes 10 through said core and a threaded hole in said core which may be aligned with the hole in said means whereby a shipment blocking screw may be threaded through said holes thereby to block relative motion between said core and magnet 15 in any direction.
3. In a contact making voltmeter, in combination, an operating magnet, a movable solenoid core therein, a screw threaded hole in said core,
4. In a contact making voltmeter, in combination, an operating solenoid magnet having a core therein, an enclosing and supporting casting for 10 said magnet, brackets on said casting on each side of said core, aligned holes in said bracket and said core, the hole in said core and one of said other holes being threaded, and a screw adapted to be passed through all of said holes and having 15 threads for engaging the threads of said threaded holes.

LANCELOT E. WENHAM.
